AIR CONDITIONER

Lewis W. Stouder, Ardmore, Okla.

Application March 15, 1935, Serial No. 11,305

2 Claims. (Cl. 261—91)

This invention relates to an air conditioner by means of which air may be cleaned and cooled. One object of the invention is to provide a device of this character of such construction that it may be readily transported from one part of a room or building to another and thus air in all portions of a large room conditioned, or the air in a number of rooms successively treated.

Another object of the invention is to so form the conditioner that when it is in use, air will be drawn through an inlet into the body portion of the device where it will be passed through a spray of fine water particles before passing out of the device and thus dust and other foreign matter removed from the air and also the temperature of the air reduced by contact with the water spray.

Another object of the invention is to retard outward movement of the air from the body by contact with a plurality of baffles which also serve as stops against which moisture in the outgoing air will catch and be prevented from passing out with the cleaned and cooled air.

Another object of the invention is to provide improved means for controlling the path of movement of the air as it passes from the conditioner and cause the blast of cleaned and cooled air to be distributed throughout a room.

Another object of the invention is to provide improved means for taking up water from the lower portion of the conditioner and causing this water to be thrown upwardly in a very fine spray or fog through which the air passes and to further so mount the water sprayer that a sump may be provided beneath it wherein dirt in the water will collect and thus make frequent changing of the water not necessary.

The improved air conditioner is illustrated in the accompanying drawings, wherein

Figure 1 is a view showing the improved conditioner in front elevation with portions broken away.

Figure 2 is a sectional view taken vertically through the conditioner.

Figure 3 is a sectional view taken transversely through the upper portion of the conditioner along the line 3—3 of Figure 2.

Figure 4 is a transverse sectional view taken through the lower portion of the conditioner along the line 4—4 of Figure 2.

Figure 5 is an enlarged view taken along the line 5—5 of Figure 2.

This improved air conditioner has a body portion consisting of a casing which extends vertically and has an upper section 1, the lower end of which telescopes into the cylindrical neck 2 of

a lower section 3, downward movement of the upper section into the lower section being limited by an outstanding head 4 which rests on the upper edge of the neck 2. Casters 5 are provided for the lower section at its corners in order that the conditioner may be readily moved from one room to another or from one portion of a room to another in case it is used in a large room. The upper and lower sections are formed of any material desired, although strong sheet metal is preferably used and walls of the lower section are lined, as shown at 6, to strengthen the same and by forming this liner of rust-proof material, rusting and corroding of the lower section will be prevented.

The upper section 1 is cylindrical in shape and of slightly less diameter than the lower section which is rectangular in cross section and this upper section is open at its upper and lower ends but at its upper end carries a head or cover 7 formed with a depending flange which fits tightly about the walls of the upper section so that a tight joint will be formed. The central portion of the head is cut out and the material of the head bent to form an annular seat 8 into which is secured the upper end of a cylindrical sleeve 9. This sleeve or cylinder is of greater length than the upper section and when the upper section is in place, the lower portion extends downwardly into the converging portion 10 of the lower section, as shown in Figure 2. As the upper end of the cylinder is firmly secured in the seat of the head or cover, this cylinder may be drawn outwardly by grasping the cover and exerting lifting movement. Between the cylinder 9 and walls of the upper section there have been arranged a plurality of baffles or deflectors 11 which extend vertically, as shown in Figure 1, and are disposed radially of the cylinder and upper section, as shown in Figure 3. These baffles may be formed of sheet metal bent to assume the desired shape, and referring to Figure 1 it will be seen that each baffle has diagonally extending portions 12 which are disposed at right angles to each other. It should be further noted that one end of each of the diagonally extending portions has been extended to form a lip 13. By this arrangement, tortuous passages will be defined between the baffles and as air passes upwardly between these baffles, moisture in the air will be deposited upon the lips and diagonally extending portions of the baffles and run or drip back into the lower section of the conditioner.

In order to draw air into the conditioner through the cylinder 9, there has been provided

a motor 14 which is disposed vertically in the cylinder axially thereof and to the projecting lower end of the motor shaft is firmly secured a fan 15. The motor is supported in the sleeve 5 or cylinder by a yoke 16 having its bridge 17 extending diametrically through the sleeve and its arms 18 extending upwardly from the bridge against walls of the sleeve. In spaced relation to the bridge the arms are bent toward each other, as shown at 19, and then upwardly to provide portions 20 which are secured against the motor by bolts 21, and above the motor the arms are again bent to form flaring portions 22, the upper ends of which are again bent to form 15 feet 23 overlying the seat 8. Through the seat are passed bolts or rivets which firmly secure them upon the bead, and in order to prevent rattling noises, rubber pads 24 are provided between the seat and feet.

20 The yoke not only serves as a carrier for the motor, but also as a support for a shaft 25 which extends axially through the sleeve 9 with its upper end rotatably received in a bearing 26 formed midway the width of the bridge 17 of the yoke.

25 The upper end of the shaft is connected with the lower end of the motor shaft 27 by a flexible connection 28 formed of rubber tubing or any other suitable material and firmly secured about the two shafts by clamps 29. The lower end of 30 the shaft 25, which may be referred to as a pump shaft or sprayer shaft, is journaled in a bearing 30 which fits into an opening formed in the hub of a spider 31, and referring to Figures 2 and 5 it will be seen that the spider is disposed in 35 bridging relation to an opening formed at the center of the bottom of the lower section. Beneath this opening is mounted a sump 32 in which dirt is to collect and in order to hold the spider in its proper position the legs of the spider are 40 equipped with depending arms or brackets 33 carrying rubber pads 34 which frictionally engage walls of the sump. There have also been provided pads 35 upon the legs of the spider which rest upon the bottom of the lower section.

45 By this arrangement the spider will be firmly held in place with the bearing 30 centered to receive the lower end of the shaft 25 and rattling noises due to contact of the spider with the floor or bottom of the lower section and walls of the sump will be eliminated.

50 Water is poured into the lower section through an opening 36 formed in a side wall thereof, which opening is normally closed by a lid or closure 37 detachably secured by bolts so that 55 it may be readily removed when additional water is necessary before the lower section of the conditioner needs to be cleaned. This water may be of any depth desired from the bottom of the lower section to the opening 36 but is 60 preferably of the depth indicated in Figure 2. This water is to be sprayed upwardly and form a fog through which air passes and in order to do so there has been provided a pump or sprayer 38 carried by the shaft 25. This sprayer is of 65 conical shape and has inner and outer walls 39 and 40, the upper edges of which are joined by an annular wall 41 having openings 42 formed therein. The shaft extends through a sleeve 43 which is axially aligned with the apex of the 70 sprayer and at the top of the sprayer there has been mounted a spider 44 having its arm riveted to the inner wall 39. The sleeve 45 at the center of the spider 44 is disposed directly above the sleeve 43 and this sleeve 45 is firmly secured about 75 the shaft 25 by a pin 46. It will thus be seen

that the sprayer will be firmly secured to the shaft to rotate therewith. The lower end portion of the sprayer is immersed in the water and when the shaft and sprayer are rotated, water will pass through openings 47 formed about the apex of the outer wall 40 and centrifugal force will cause this water to move upwardly through the space between the walls of the sprayer to the upper end thereof where it will be discharged as a spray through the openings 42 in the marginal walls 41. The fact that the sprayer is rotating at a rapid rate of speed will cause the sprayed water to be thrown upwardly and outwardly as very fine water drops thus forming a thick fog which fills the lower section of the air conditioner. During this operation the fan draws air inwardly through the sleeve or cylindrical column 9 and forces the air downwardly through the sleeve to the open lower or inner end thereof where it passes into the lower section of the air conditioner. Upon entering the lower section of the air conditioner, the air will move toward the sides thereof and upwardly through space about the sleeve. The air, of course, passes through the water fog which causes dust and other foreign substances to be taken up by the water drops and also reduce the temperature of the air. During upward movement of the air about the sleeve 9 it passes through the tortuous passages between the baffles 11 and moisture will be deposited upon the lips and end portions of these baffles. It will thus be seen that the water fog will be confined within the air conditioner and the water which will accumulate upon the baffles and walls of the upper and lower sections will flow back into the bottom of the lower section where dirt will gravitate through the water to the bottom of the lower section and into the sump. The baffles terminate in spaced relation to the upper end 40 of the upper section 1, and above the baffles the upper section is formed with an outlet opening surrounded by a collar or neck 48. Blades or louvers 49 are pivotally mounted in the neck 48, as shown in Figures 2 and 3, and inner end 45 portions of the blades carry arms or brackets 49' pivoted to a cross bar or strip 50 to cause the blades to move simultaneously about their pivots when reciprocating motion is imparted to the cross bar by a link 51 extending from the outer end of a lever 52. This lever is pivoted upon a hanger 53 and has a fork 54 at its inner end engaging the eccentric pin 55 of a gear 56 meshing with a small pinion 57 carried by the shaft of the motor and, therefore, the lever will be rocked about the hanger as a pivot to impart oscillating movement to the blades when the conditioner is in use. Since these blades swing about their pivots transversely of the outlet neck or mouth 48, air which passes out through this mouth will be directed toward different portions of a room as the blades move. It will thus be seen that warm and dusty air in a room may be drawn into the conditioner where it is passed through a water fog to remove dust and reduce its temperature and then returned to the room through the outlet as clean and cooled air. As the device is provided with casters it may be very easily moved from one portion of a large room 70 to another or transferred from one room to another. It will be obvious that an air conditioner constructed in accordance with this disclosure may be erected as an immovable device in a permanent location.

Having thus described the invention, what is claimed as new is:

1. An air conditioner comprising a casing having an air inlet opening at its top and an air outlet in its upper portion, a sleeve extending vertically in the casing from the air inlet with its lower end spaced from the bottom of the casing, a yoke in the sleeve having a bridge extending transversely across the sleeve and arms extending upwardly through the sleeve against walls thereof, the arms having their upper portions bent to converge upwardly and being then extended upwardly in spaced parallel relation to each other and then bent to diverge upwardly and having their upper ends secured at the top of the sleeve, a motor secured between the spaced parallel portions of the arms of said yoke in a vertical position with its shaft disposed axially of the sleeve, a fan carried by the motor shaft for drawing air inwardly through the inlet and forcing the air through the sleeve into the lower portion of the casing for passage upwardly about the sleeve to the outlet, a bearing at the bottom of the casing, a sprayer shaft disposed vertically with its lower end mounted in the bearing and its upper portion journaled through the bridge of the yoke and connected with the shaft of the motor to rotate therewith, a sprayer carried by the sprayer shaft for spraying water upwardly in the casing and forming a water fog through which the air passes, the motor, fan,

sprayer shaft and sprayer being removable upwardly through the sleeve with the yoke as a unit, and means about the sleeve for extracting water from air passing upwardly about the sleeve to the outlet.

5

2. An air conditioner comprising a casing having an air inlet at its top and an outlet in its upper portion, a sleeve leading from the inlet and having its lower end spaced from the bottom of the casing, means for passing air through the inlet and sleeve into the lower portion of the casing including a motor mounted vertically in the sleeve, a sprayer in the lower portion of the casing for spraying water and forming a water fog through which the air passes, means for extracting water from air as the air passes upwardly about the sleeve toward the air outlet, blades in the air outlet spaced from each other and movably mounted for directing discharge of air from the outlet, the blades being connected for simultaneous movement, and means for imparting movement to said blades including a bar pivotally mounted for oscillating movement and having one end portion extending into the sleeve transversely thereof and formed with forks, a gear rotatably mounted and receiving rotary motion from said motor, and an eccentric pin carried by said gear and engaged between forks of the shaft for imparting oscillating movement thereto as the gear rotates.
